(57) **CLAIM**

I claim the ornamental design for an insulated upper section of tent, as shown and described.

DESCRIPTION

FIG. 1 shows a top and side perspective view of an insulated upper section of tent.

FIG. 2 shows a front elevation view thereof, the 60 degree offset elevational views in either direction being identical thereto.

FIG. 3 shows a rear elevation view thereof, the 60 degree offset elevational views in either direction being identical thereto.

FIG. 4 shows an additional side view thereof, the 60 degree offset elevational views in either direction being identical thereto.

FIG. 5 shows a top plan view thereof; and,

FIG. 6 shows a bottom plan view thereof.
